UNITED STATES PATENT OFFICE.

FRED J. LATHAM, OF RUMFORD, MAINE, ASSIGNOR TO THE OXFORD PAPER COMPANY,
A CORPORATION OF MAINE.

SUCTION BOX FOR PAPER-MAKING MACHINES.

Application filed September 16, 1925. Serial No. 56,592.

My invention relates particularly to suction boxes used for the removal of the water from paper making machines, and is applicable to paper making machines of various different kinds.

The object of my invention is to provide suction boxes for paper making machines having many advantages over previous types of suction boxes. More particularly, the object is to provide an improved cover for suction boxes, that is to say, an improved construction for the upper portion of the suction boxes, which is adapted to support the Fourdrinier wire carrying the paper web to be dried. Suction boxes made in accordance with my invention have the advantage of wearing off level and smooth and not in ridges under the Fourdrinier wire supported thereby. In carrying out my invention I may accomplish this purpose by providing suction box covers made of pieces of wood of such a character as to wear off smoothly and without the formation of any substantial ridges under the action of the Fourdrinier wire. Preferably, for this purpose I provide such covers made of wood and in which the grain runs so that the longitudinal grain of the wood extends in a direction cutting through the path of movement of the Fourdrinier wire, for example, vertically, or at right angles to the plane of the Fourdrinier wire. These covers may be supported in any desired manner but I prefer to support them in metal supports having appropriate recesses for receiving the same. A further object is to provide covers of this character so as to not only prevent the formation of uneven surfaces on the covers but also so as to prevent the formation of ridges in the Fourdrinier wire with consequent possibility of damage to the paper web. Again, a further object is to obviate the necessity of planing off the top of the cover at frequent intervals during the life of a Fourdrinier wire, inasmuch as covers made in accordance with my invention need not be planed down except, perhaps, when changing to a new Fourdrinier wire. Accordingly, there is a saving of time and labor in using covers made in accordance with my invention.

Further objects of my invention will appear from the detailed description of the same hereinafter.

While my invention is capable of embodied

ment in many different forms for the purpose of illustration I have shown only one form of the same in the accompanying drawings, in which

Figure 1 is a diagrammatic side elevation of a paper making machine equipped with suction boxes made in accordance with my invention;

Figure 2 is a plan view of the same;

Figure 3 is an enlarged vertical section of one of the suction boxes;

Figure 4 is an enlarged vertical section of the same taken at right angles to Figure 3 on line 4-4 therein; and

Figure 5 is a plan view of one of the suction box covers.

In the drawings I have shown a paper making machine comprising a stock supply box 1 and a breast-roll 2 for supporting a Fourdrinier wire 3 at one end of the machine. Said wire passes over a plurality of table-rolls 4 and thence over two suction boxes 5 and 6, a supporting-roll 7, then between a supporting-roll 8 and a dandy-roll 9 and thereafter over two further suction boxes 10 and 11. From this point the wire passes over a guide-roll 12, a suction-couch-roll 13 and thence in the reverse direction in contact with five wire carrying and stretch rolls 14, 15, 16, 17 and 18. Each of the suction boxes is comprised of a housing 19 provided with a vacuum chamber 20 therein supplied with a vacuum from any suitable source. In the interior of the housing there are any desired number of supporting bridges 21 shaped like an inverted U and adapted to support at their upper portions a number of suction box covers, each of which is comprised of a metal grooved support 22 having a dovetailed recess 23 therein and secured to the housing 19 and the bridges 21 by means of screws 24. The dovetailed recess 23 is provided for receiving a plurality of wooden blocks 25, 26 and 27 arranged end to end so as to extend completely across the Fourdrinier wire 3. These blocks 25, 26 and 27 are mortised together at their ends, as shown in Figure 5, and are so arranged that the longitudinal grain of the same extends in a direction which cuts through, for example, vertically, the plane of the wire 3. Furthermore, as shown in Figure 5, the said blocks of wood are preferably so arranged that the grain on the upper faces of the said blocks ex-

tends substantially crosswise of the wire. In order to assist in holding the covers in proper position with regard to the housing 19, a number of blocks 28 are provided which are secured by bolts 29 to the housing 19, said blocks being located adjacent the side of the bridges 21.

In the operation of my invention, as the wire 3 travels in the direction of the arrow, 10 as shown in Figure 3, the blocks 25, 26 and 27 will wear evenly and smoothly under the action of the wire, thus preventing channelling and preventing the formation of ridges in the surfaces of the same. Accordingly, also, the formation of corresponding 15 ridges or unevennesses in the wire will be avoided. Furthermore, loss of time and labor, due to frequent smoothing out any unevennesses in the surfaces of the blocks 25, 26 20 and 27, will be avoided inasmuch as it will not be necessary to re-surface said blocks by planing or otherwise except, perhaps, when a new Fourdrinier wire is installed.

While I have described my invention 25 above in detail I wish it to be understood that many changes may be made therein without departing from the spirit of the same.

I claim:

30 1. In a paper making machine, the combination of a Fourdrinier wire and a suction box having a cover comprising a wooden block having the longitudinal grain of the wood extending in a direction which cuts 35 through the path of the wire, at right angles thereto, and so arranged that the annual growth rings in the face of the block extends crosswise of the wire.

2. In a paper making machine, the combination of a Fourdrinier wire and a suction 40 box having a cover comprising a wooden block having the longitudinal grain of the wood extending in a direction which cuts through the path of the wire, said block being carried in a grooved support set into the 45 face of the block.

3. In a paper making machine, the combination of a Fourdrinier wire and a suction 50 box having a cover comprising a wooden block having the longitudinal grain of the wood extending in a direction which cuts through the path of the wire and at right angles thereto, said block being carried in a grooved support set into the face of the 55 block.

4. In a paper making machine, the combination of a Fourdrinier wire and a suction 60 box having a cover comprising a wooden block having the longitudinal grain of the wood extending in a direction which cuts through the path of the wire, at right angles

thereto, and so arranged that the annual growth rings in the face of the block extends crosswise of the wire, said block being carried in a grooved support at the base of the block.

5. In a paper making machine, the combination of a Fourdrinier wire and a suction box having a cover comprising wooden blocks having the longitudinal grain of the wood extending in a direction which cuts through the path of the wire, said blocks being carried in a dovetailed support, the blocks being mortised together at their ends.

6. In a paper making machine, the combination of a Fourdrinier wire and a suction box having a cover comprising wooden blocks having the longitudinal grain of the wood extending in a direction which cuts through the path of the wire and at right angles thereto, said blocks being carried in a dovetailed support, the blocks being mortised together at their ends.

7. In a paper making machine, the combination of a Fourdrinier wire and a suction box having a cover comprising wooden blocks having the longitudinal grain of the wood extending in a direction which cuts through the path of the wire, at right angles thereto, and so arranged that the annual growth rings in the faces of the blocks extends crosswise of the wire, said blocks being carried in a dovetailed support, the blocks being mortised together at their ends.

8. In a paper making machine, the combination of a Fourdrinier wire and a suction box having a cover comprising spaced wooden blocks placed end to end carried by grooved supports.

9. In a paper making machine, the combination of a Fourdrinier wire and a suction box having a cover comprising a plurality of wooden blocks carried by dovetailed supports, said supports being of substantially the same outside width as the block.

10. In a paper making machine, the combination of a Fourdrinier wire and a suction box having a cover comprising wooden blocks carried by a dovetailed support, the blocks being mortised together at their ends.

11. In a paper making machine, the combination of a Fourdrinier wire and a vacuum box comprising a plurality of covers comprised of spaced wooden blocks placed end to end carried in grooved supports and having supporting bridges associated therewith.

In testimony that I claim the foregoing, I have hereunto set my hand this 8th day of September, 1925.

FRED J. LATHAM.
